ASPHALT STRIP SHINGLE

Louis Herscovitz, Park Ridge, Ill., assignor to The
Ruberoid Co., New York, N. Y., a corporation of
New Jersey

Application April 23, 1940, Serial No. 331,074

9 Claims. (Cl. 108—7)

This invention relates to shingles for covering roofs or the like, and more particularly to an improved asphalt strip shingle.

These shingles are cut from sheets of prepared roofing material to form a plurality of joined but spaced-apart shingle-like tabs, which when the strips are laid give the appearance of a covering composed of individual shingles of the shape of the shingle-like tabs.

They have the advantage of economy and ease in laying, but because of the material of which they are made being usually only about $\frac{1}{8}$ " to $\frac{1}{16}$ " thick, they do not cast appreciable shadows along the butts of the courses as do thicker shingles, such as wood and slate.

From an ornamental standpoint, such shadows are desirable since they tend to relieve the flat appearance of the covering. It is one of the objects of the invention to overcome this deficiency of the ordinary asphalt strip shingle.

According to my invention, I provide a shingle having a zone formed of alternate narrow ridges and valleys extending transversely of the strip and forming a longitudinal band that is so disposed on the surface of the strip as to be visible under the butt edges of overlying strips. This produces a shadow effect immediately below each course of butts and accentuates their thickness.

Other objects and advantages of the invention will appear from the following description thereof, reference being had to the accompanying drawing, in which—

Figure 1 is a plan view of a conventionalized asphalt strip shingle embodying the invention;

Fig. 2 is a plan view of several such strips arranged in three overlapping courses;

Fig. 3 is a detailed sectional view on the line 3—3 of Figure 1; and

Fig. 4 is a fragmentary section on the line 4—4 of Figure 1.

The strip shingle 10 is made of sheet material having a base 11 of roofing felt saturated with asphalt or other suitable waterproofing substance and having a coating 12, usually of similar bituminous substance but generally of a harder consistency, extending over the entire upper surface of the sheet, which coating is faced with particles 13 of mineral matter, such as crushed slate. A second layer or overlay 14 of the bituminous coating substance is applied over the first coat 12 and mineral particles 13 and is faced with mineral particles 15, preferably colored granules. The overlay coating 14 preferably extends over the entire surface of the strip although it may extend only up to the top edge of the band X hereinafter described. The granules in the area of the band X may be of a contrasting or darker color than those on the rest of the face of the shingle.

The sheet material is cut to form strips hav-

ing shingle-like tabs 16, separated by recesses 17 of complementary form. In the preferred embodiment of the invention illustrated in the drawing these tabs and complementary recesses are rectangular, although they may be of any other shape. The exposed surfaces of the tabs 16 and the portion of the strip below the band X may be plain or textured, as desired. A small tab 18 of semi-circular or other form may be provided at one end of the body of the shingle 10 and corresponding recess 19 at the other end for convenience in aligning the shingles of a course, one with another.

After the coatings of asphalt and mineral particles have been applied, and preferably before the strips have been cut, the sheet is impressed or embossed with a suitable embossing roll or other suitable means to form a band X of alternating depressions or valleys 20 and ridges 21 in the top coating. The valleys are formed by pressing the mineral particles 14 in the area of the band, so that they are embedded in the coating, thus somewhat darkening the valleys as by extrusion of the asphalt coating. The band X composed of these valleys 20 and ridges 21 is approximately $2\frac{1}{4}$ " wide and is so disposed on the body portion of the strip that when the strips are applied, as indicated in Fig. 2, a portion of the length of the band of the strips of one course A will be exposed below the butt edge of the tabs 16 of the strips of each third course C, while portions of the band on the strips of the second course B will likewise be exposed in the recesses 17 of the strips of each third course C. These exposures give the covering the desired shadow effect and tend to increase the apparent thickness of the butts.

In using the term "ridges" to define the portions 21 that intervene the depressions 20, it is to be understood that they need not project upwardly beyond the plane of the upper surface of the strip. It will be seen that the ridges 21 and valleys 20 extend in a general direction transverse of the strip but are somewhat inclined or curved and not parallel to one another throughout the length of the band. This has the advantage that when wind drives rain across a pitched roof having a covering of such strips, the depressions tend to act as dams or barriers and to direct the rainwater down from the butts in different and diverging paths.

The strips are generally laid from the eaves of the roof up, the lowest course being applied first, and so on. The strips of each course are laid with the butt edges of the tabs 16 in registration with the upper edges of the recesses 17 of the strip of the next lower course, and when so laid these edges lie on or just below the upper edge of the bands X of two lower courses, respectively, as hereinbefore described.

In some instances the second coating or over-

lay of asphalt 14 and mineral granules 15 may be omitted, in which case the coating 12 may be made somewhat thicker than usual and the valleys 20 and ridges 21 may be formed therein. 5 Other modifications may be made within the scope of the invention as herein described and claimed.

I claim:

1. A shingle comprising a strip of waterproofed fibrous material coated on its entire upper surface with a layer of bituminous substance faced with mineral particles, and having a second coating layer of bituminous substance and mineral particles over the first layer, said shingle having 10 tabs separated by recesses of complemental form along the lower edge of its body portion, and a band extending lengthwise of the strip formed of alternate transversely extending depressions and ridges, said band being disposed on the upper 15 surface of the body of the strip intermediate its upper and lower edges in position to be exposed below the lower edge of the body portion of the strips of the next succeeding course and below 20 the butt edges of the tabs of the strips of the 25 third succeeding course.
2. A shingle comprising a strip of waterproofed fibrous material coated on its entire upper surface with a layer of bituminous substance faced with mineral particles, and having a second coating 30 layer of bituminous substance and mineral particles over the first layer, said shingle having tabs separated by recesses of complemental form along the lower edge of its body portion, and a band extending lengthwise of the strip formed 35 of alternate depressions and ridges variously inclined in the direction of the width of the strip, said band being disposed on the upper surface of the body of the strip intermediate its upper and lower edges in position to be exposed 40 below the lower edge of the body portion of the strips of the next succeeding course and below the butt edges of the tabs of the strips of the 45 third succeeding course.
3. A shingle comprising a strip of waterproofed fibrous material coated on its entire upper surface with a layer of bituminous substance faced with mineral particles, and having a second coating 50 layer of bituminous substance and mineral particles over the first layer, said shingle having tabs separated by recesses of complemental form along the lower edge of its body portion, and a band extending lengthwise of the strip formed of alternate depressions and ridges variously 55 inclined in the direction of the width of the strip and being generally non-parallel to one another throughout the length of the band, said band being disposed on the upper surface of the body of the strip intermediate its upper and lower edges in position to be exposed 60 below the lower edge of the body portion of the strips of the next succeeding course and below the butt edges of the tabs of the strips of the third succeeding course.
4. A shingle comprising a strip of roofing felt having on its upper surface two layers of bituminous coating substance each faced with particles of mineral matter, one surfaced on the other, said strip having the lower edge of its body portion formed with alternate tabs and

recesses of complemental form, and a band extending lengthwise of the body of the strip intermediate its upper and lower edges, said band being formed in a series of spaced apart depressions in the second coating layer extending across 5 the width of the band.

5. A shingle comprising a strip of roofing felt having on its upper surface two layers of bituminous coating substance each faced with particles of mineral matter, one surfaced on the other, said strip having the lower edge of its body portion formed with alternate tabs and recesses of complemental form, and a band extending lengthwise of the body of the strip intermediate its upper and lower edges, said band 10 15 being formed in a series of spaced apart depressions in the second coating layer extending across the width of the band and at various inclinations to its longitudinal edges.

6. A shingle strip comprising a fibrous base 20 coated with two superposed layers of bituminous substance each faced with mineral particles, the second layer being faced with colored particles, said strip having tabs spaced apart along the lower edge of its body portion, and a series of 25 alternate ridges and depressions forming a band that extends lengthwise of the body of the strip intermediate its upper and lower edges, the depressions extending into the second coating layer with the mineral particles thereof substantially 30 covered by the extruded coating substance to give the depressions a darker color than the intervening ridges.

7. A shingle strip comprising a fibrous base coated with two superposed layers of bituminous 35 substance each faced with mineral particles, the second layer being faced with colored particles, said strip having tabs spaced apart along the lower edge of its body portion, and a series of alternate ridges and depressions forming a band 40 that extends lengthwise of the body of the strip intermediate its upper and lower edges, the mineral granules in the area of said band being of contrasting shade or darker color from those on the rest of the shingle strip below the band. 45

8. A shingle strip comprising a fibrous base coated with a waterproof bituminous coating substance faced with mineral particles, said strip having tabs spaced apart along the lower edge 50 of its body portion, and a series of alternate ridges and depressions forming a band that extends lengthwise of the body of the strip intermediate its upper and lower edges in position to be exposed immediately below lower edge portions of two succeeding courses. 55

9. A shingle strip comprising a fibrous base coated with a waterproof bituminous coating substance faced with mineral particles, said strip having tabs spaced apart along the lower edge 60 of its body portion, and a series of alternate ridges and depressions forming a band that extends lengthwise of the body of the strip intermediate its upper and lower edges in position to be exposed immediately below lower edge portions of two succeeding courses, the mineral 65 particles in the area of the band being of a darker shade or color than those on the rest of the face of the strip.

LOUIS HERSCOVITZ.
